UNITED STATES PATENT OFFICE.

GEORGE H. FORSYTH, OF CHICAGO, ILLINOIS.

WINDOW.

1,086,284.

Specification of Letters Patent. Patented Feb. 3, 1914.

Application filed April 6, 1908. Serial No. 425,467.

To all whom it may concern:

Be it known that I, GEORGE H. FORSYTH, a citizen of the United States, residing at Chicago, in the county of Cook and State of Illinois, have invented certain new and useful Improvements in Windows, of which the following is a specification.

This invention relates to improvements in windows, and has reference more particularly, although not exclusively, to car windows.

Certain features of improvement relate to the sash frame, which is constructed of sheet metal suitably bent to form hollow stiles and bars, reinforced to secure sufficient strength and rigidity.

Other features of improvement relate to a novel means of attaching a sash lock, with means whereby the latter is caused to operate with the sash guide in effecting a snug fit of the sash in the guide, and still other minor features of improvement will hereinafter appear from the following description of the invention.

My invention will be readily understood, both with respect to its structural features and the mechanical advantages and improvements secured thereby, when considered in connection with the accompanying drawings illustrating some practical embodiments thereof, in which—

Figure 1 is an elevational view of a portion of a window frame or casing with the sash therein, the parts being broken away both horizontally and vertically and the base members of the inner sash guides appearing in vertical section. Fig. 2 is a vertical transverse section on the line 2—2 of Fig. 1, viewed in the direction indicated by the arrows, and also showing a section of the sill and my improved sash-cushioning device mounted thereon. Fig. 3 is a cross-sectional detail on the line 3—3 of Fig. 1, looking in the direction indicated by the arrows. Fig. 4 is a view similar to Fig. 3, but showing different forms of bent sheet metal sash guides. Fig. 5 is a fragmentary front elevation of the lower corner part of the sash and sill shown in Fig. 2, viewed in the direction indicated by the arrow 5 in the latter figure. Fig. 6 is a fragmentary outer edge elevation of the sash and its guides, as viewed from the left of Figs. 1 and 3. Fig. 7 is a detail sectional view 55 showing the arched form of glazing strip. Fig. 8 is a detail longitudinal sectional view

through one of the hollow stile members showing the cross sectional shape of one of the rivets which connects the overlapping portions of said stile member.

Referring to Figs. 1 to 3, inclusive, and 5 and 6, 1 designates the sill, and 2 and 3 the inner and outer stops or strips forming between them guide-grooves in which the stiles of the sash are adapted to slide. The 65 guide-strips 2 and 3 are shown as substantially hollow sheet metal members having on their outer sides laterally projecting flanges by which they are secured to the jamb or casing by screws 4. In Fig. 4, 70 the guide-strips 2^a and 3^a are formed with inclined or oblique portions 2^b and 3^b, through which pass in an oblique or inclined direction the securing screws 5, this construction affording a simple means of insuring 75 a snug sliding fit of the sash in its guides after the sash has been inserted, by simply additionally turning up the screws 5. 6 designates as an entirety the upper and lower horizontal sash bars, and 7 the side 80 bars or stiles of the sash, which are in all cases formed from a sheet metal strip or a seamless tube bent to the required cross-sectional shape and provided with an inwardly projecting lip 8 that forms a shoulder or stop for the margin of the glass 9. The edges of this latter are embraced by channel-strips 10 of rubber or similar insulation, and the glass is securely held in the sash by glazing strips 11, each of these 90 strips comprising a transversely elastic metal strip substantially triangular shaped in cross-section and having inner and outer lips 11^a and 11^b (Fig. 3) adapted to bear against the adjacent side of the insulator 10, 95 said strip being secured by a series of screws 12 passed obliquely through the glazing strip and tapped into the adjacent inner wall of the sash stile or bar; said screws preferably being screwed into thick short 100 rivets 13 by which the overlapping sections constituting the inner wall of the stile are secured together. 14 designates as an entirety the adjusting strip which is preferably, although not necessarily, employed in 105 connection with the other features of the invention. This adjusting strip is formed from a piece of thin resilient sheet metal that is bent or doubled upon itself on substantially its median longitudinal line, the 110 inner portion being further bent longitudinally to suitably engage the stile and in

some cases secured to the latter, while the outer portion is also suitably bent longitudinally to afford a bearing upon both the inner sash strip and the bottom wall of the 5 guide-grooves. The longitudinal bend between the inner and outer portions of the adjusting strip is indicated at 15, the portions engaging the side and edge of the sash stile are indicated at 16 and 17, respectively, 10 and the portions engaging the guide-strip 2 and the bottom wall of the groove are indicated at 18 and 19, respectively. It will be observed that at the several longitudinal bends or folds of the strip the metal is 15 preferably expanded transversely, producing well rounded flexible corners.

In Figs. 3 and 4, the adjusting strip 14 is shown as secured at 20 to the outer margin of the sash stile 7, being bent inwardly and 20 forced into a suitable slot or kerf in the latter. The meeting ends of the bars and stiles of the sash are mitered, as usual, and are rigidly united through the agency of internal angle-pieces 28, to which said members 25 are secured by screws or rivets 29.

Figs. 2, 3, and 4 show that the side and outer walls of the stile, including the lip 8, are of single thickness, the inner wall being of a double thickness formed by the over- 30 lapping of the adjacent marginal portions of the strip, these internal and external overlapping marginal portions being indicated at 30 and 31, respectively.

The overlapping and, in some cases, doubled or folded sections making up the inner wall of the sash frame member may be secured together simply by the binding effect of the screws 12 by which the glazing strip is attached; but, as already stated, I prefer 40 to independently unite these members through the agency of the wide rivets 13, which latter are preferably oblong in cross-section as shown in Fig. 3 to prevent turning during the drilling thereof for the screws 45 12, and the heads of which are countersunk in the outer face of the wall so as to avoid interference with the glazing strip. This construction not only more securely unites the parts making up the multiple thickness 50 of the wall of the stile or bar, but also affords a more secure anchorage for the screws or bolts 12.

Referring once more to the glazing strip 11 and its securing means, it will be seen 55 that the walls of this strip at the points where they are engaged by the screws 12, are preferably provided with transverse slots shown, for instance, at 48 and 49 for the passage of the screws, permitting some 60 transverse play of the adjusting strip relatively to the screws to allow for variations in the thickness of the glass, it being noted that the cross-sectional contour of the glazing strip is such that, under the action of 65 the screws, the strip is automatically wedged

and crowded against the glass, the transverse elasticity of the glazing strip further acting as a nut lock to prevent the screws from working loose. The outer or inclined surface of the strip is also preferably 70 slightly arched, as shown in Fig. 7, to facilitate this latter action, and maintain a substantially continuous engagement with the inner side of the screw-head.

Referring next to the means for cushioning the lower edge of the sash on the sill of the window frame, which means are best shown in Figs. 2 and 5, 50 designates a ribbon spring of serpentine form that lies in a shallow groove or channel 51 formed in and lengthwise of the upper face of the sill 1 directly below and in the vertical plane of the sash. Overlying this spring and forming a contact member for the lower edge of the sash is a sheet metal plate 52, which latter preferably has on its inner edge an 55 upstanding lip or flange 53 (Fig. 2) in sliding interlocked engagement with a hollow metal strip 54 mounted on the sill 1 on the inner side of the window, and, on its outer edge, an inclined facing 55 constituting a finish for the inclined outer face of the sill 1. As the spring 50 normally tends to raise the contact-member 52, the sash will be cushioned thereby when it is lowered, and 60 the upwardly forcing tendency of the spring 50 will always maintain a close fit between the contact strip 52 and the lower edge of the sash.

Referring now to my improved means for 100 mounting the lock commonly employed on car windows, and which lock may be applied either on one side only, or on both sides, as indicated in Fig. 1 of the drawings, 56 designates the casing of a known and usual form 105 of lock, 57 designating the locking plunger, and 58 and 59 the stationary and movable pinch-handles, respectively, by which the plunger 57 is retracted when the sash is to be raised. 60 designates a supporting plate or 110 base for the lock, which plate is provided on its outer and lower edges, respectively, with tenons 61 and 62. The tenon 61, as shown best in Figs. 3 and 4, enters a slot formed in the inner edge of the lip 8 of the stile and is 115 secured to the adjacent side wall of the stile as by a screw or rivet 63; while the lower tenon 62, as best shown in Fig. 2, enters a similar slot in the upper edge of the lower transverse bar 6 of the sash and is similarly 120 secured to the adjacent side wall of said bar as by a screw or rivet 64. Preferably, the securing tenons 61 and 62 enter the stile and bar of the sash at points within the space occupied by the connecting angle-piece 125 28, in which case said angle-piece is suitably slotted or cut away to permit the entrance of said tenons. To facilitate the application of the plate 60 to the sash during the assembling of the latter, the slotting or mor- 130

tising of one limb of the angle-pieces will be of a sufficient longitudinal extent to permit the entrance of either tenon 61 or 62 and the subsequent sliding movement of the other sash-member and the angle-piece vertically or horizontally, as the case may be, toward the edge of the plate to effect the entrance of the other tenon to its proper position in the other member of the sash. For instance, 10 the upright limb of the angle piece 28 at the lower left hand corner of Fig. 1 is slotted, mortised or recessed from its upper end downwardly at least to the bottom edge of the tenon 61. The tenons 61 and 62, as best 15 shown in Fig. 2, are inwardly offset relatively to the plate 60, and the lock-casing 56 is attached to said plate as by screws 65. To relieve the said screws of strain, I preferably extend the upper end of the plate 60 20 and overturn the same, as shown at 66 (Fig. 2) to form an abutment for the upper edge of the lock-casing 56; while the lower edge of the plate 60 to one side of the tenon 62 is likewise preferably extended and turned up 25 to form a shoulder or abutment 67 (Fig. 2) for the lower edge of the lock-casing. By this means all vertical strains imparted to the lock-casing through the plunger are received and resisted by the integral abutments 66 and 67 of the plate 60; and consequently all the screws 65 are relieved of such strain.

While the plate 60 as above described constitutes a base or support for the lock-casing, it also performs an additional and valuable function as a corner fillet or reinforcement for the corner joint of the sash frame, thus permitting the use of relatively narrow stiles and bars without detracting 35 from the strength and rigidity of the sash frame, and thus permitting, through the employment of narrow stiles and bars, a larger total area of glazing than would otherwise be possible.

40 By reference to Fig. 6 it will be observed that the opening 68 in the sash-guide member 2 through which the locking plungers 57 of the lock enters is provided with an inclined wall 69, and the face of the plunger 57 adjacent thereto is correspondingly inclined or beveled, as shown at 70, the end of the plunger 57 being shown in elevation. Furthermore, the cross-section of the plunger is somewhat smaller than the area of the opening. 45 By reason of this construction, when the plunger is engaged with the opening, the weight of the sash acting through said plunger causes the inclined side 70 of the plunger to ride down the inclined edge 69 of the opening, which action forces the sash laterally toward the opposite sash-guide 3, thus producing a snug fit between said guide and the sash.

With reference to the described internal 50 reinforcement of the sash frame members, it

may be noted that, while I have illustrated this reinforcement as applied to both the stiles and bars, it is of especial advantage in its application to the horizontal bars, since they are subjected to the greater strain, the 70 stiles being to some extent supported through their engagement with the guides.

While I have described and illustrated my improvements as applicable to windows, yet I do not limit them to this particular application to the extent that the various features of construction are or may be applicable to analogous structures, such as doors, panels, and the like.

I claim:

1. The combination with a sash comprising hollow members, and an internal reinforcing piece at the corner thereof, of an external fillet having a mortise and tenon engagement with the sash members and with 85 the internal reinforcing piece, substantially as described.

2. In combination, a sash frame comprising hollow members having their adjacent ends provided with an internal reinforcement piece forming a connection therebetween, and a sash attachment secured to and supported by the reinforcement piece in the angle formed by the interior edges of the sash members, substantially as described. 95

3. In combination, a sash frame comprising hollow members, reinforcement pieces telescopically engaging within and connecting adjacent frame members, and an external sash attachment having a mortise and 100 tenon engagement with the internal reinforcement pieces.

4. In combination, a sash frame comprising hollow members, reinforcement pieces telescopically engaging within and connecting adjacent frame members, and an external lock plate having inwardly extending offset portions entering the frame and reinforcement piece and also having marginal 110 outwardly and reversely bent lips adapted to overlie and secure a lock in place.

5. The combination with a sash, of a corner fillet plate applied thereto, and a separate sash-lock mounted on said fillet and rigidly supported thereby in the angle 115 formed by the inner edges of the sash members.

6. The combination with a hollow sash frame having an internal reinforcing piece at a corner thereof, of a corner fillet having 120 tenons entering mortises in said sash frame and reinforcing piece.

7. The combination with a sash, of a supporting plate for a sash-attachment secured thereto, said supporting plate having a bent 125 marginal portion adapted to overlap the adjacent edge of the attachment and also having mortise and tenon engagement with the sash.

8. In combination, a sash including hol- 130

- low members connected at an angle to form a corner, a lock plate connected to the inner edges of adjacent members, and a reinforcement within the adjacent members, the lock plate connection to the sash also extending into the reinforcement, substantially as described.
9. In combination, a sash including hollow members connected at an angle to form a corner, a lock plate connected to the inner edges of adjacent members, an L-shaped reinforcement within the adjacent members, the lock plate connection to the sash also extending into each limb of the L-reinforcement, substantially as described.
10. In combination, a hollow metal sash comprising narrow sash members, a reinforcing plate secured thereto, and a lock attached to the plate, the lock operating members extending into the area bounded by the inner edges of the sash.
11. In combination, a hollow metal sash comprising narrow sash members, a reinforcing plate secured thereto, and a lock attached to the plate, the lock operating members extending into the area bounded by the inner edges of the sash, and the connections between the lock and sash members lying in part at least within the planes of the faces of the latter.
12. In combination, a hollow metal sash comprising narrow sash members, a reinforcement within the sash, a lock plate extending into the area bounded by the inner edges of the sash and connected through the sash to the interior reinforcement, and a lock carried by the plate.
13. In combination, a sash including narrow stiles, a lock embraced within the area bounded by the sash and connected to the sash members, the lock plate having an integral portion interlocking with a sash member and with the inner reinforcement, substantially as described.
14. In combination, a sash including members connected at an angle to form a corner, a stiffening plate disposed in part at least within the angle formed by the inner edges of the sash and connected to the adjacent sash members, and a lock carried by said plate, substantially as described.
15. In combination, a sash including a narrow hollow stile, a lock plate mounted thereon and a lock on the plate and overlying in part at least the glass area of the sash and connected to the narrow stile, substantially as described.
16. In combination, a sash including a narrow hollow stile a lock-plate mounted thereon, and a lock on the plate and overlying in part at least the glass area of the sash and connected to the narrow stile, the lock connections to the stile lying in part at least within the planes of the side faces of the latter, substantially as described.

GEORGE H. FORSYTH.
